SPEAKER UNIT

William A. Ellmore, Wilmette, Ill., assignor to
Utah Radio Products Company, Chicago, Ill., a
corporation of Illinois

Application July 2, 1934, Serial No. 733,367

4 Claims. (Cl. 179—119)

The invention relates generally to devices for transforming electrical vibrations into sound vibrations and more particularly to a device of the type generally known as a magnetic speaker.

5 A general object of the invention is to provide a novel device of this character having an improved arrangement and relationship of parts by which simplicity of manufacture, ease of assembly, and accuracy of adjustment are achieved.

10 Another object is to provide a device having high operating efficiency.

Another object is to provide a new and improved device wherein the voice coil is disposed in substantially the closest possible relation to the armature which is responsive to the energizations thereof whereby to obtain maximum efficiency in operation.

Another object is to provide novel means for suspending the armature for movement according to voice coil energizations which is fashioned to permit rapid assembly of the armature structure into a rigid unit and which includes an adjustable mounting by which the position of the armature may be accurately determined and maintained and the proper restoring force imposed thereon.

Further objects are to provide novel means for supporting the cone mounting in fixed relation to the mechanism by which the cone is driven or vibrated, and for obtaining accurately the precise relationships required in the assembly of the several elements comprising the cone driving mechanism.

Other objects and advantages will become apparent in the following description and from the accompanying drawings, in which:

Figure 1 is a fragmentary rear view in elevation of a device embodying the features of the invention.

Fig. 2 is an enlarged fragmentary central section through the device taken along the line 2—2 of Fig. 1.

Fig. 3 is an enlarged view showing a detail of the cone mounting or supporting member.

Fig. 4 is a distended view in perspective of the several elements forming a part of the means by which the armature is supported.

Fig. 5 is a fragmentary sectional view of the cone driving mechanism taken as indicated by the line 5—5 of Fig. 6, the cone support being omitted for clarity.

Fig. 6 is a sectional view of said mechanism taken along the irregular line 6—6 of Fig. 5.

Fig. 7 is a sectional view of said mechanism taken transversely thereof on the line 7—7 of Fig. 5.

Fig. 8 is a fragmentary perspective view of the armature and pole piece assembly.

Fig. 9 is an exploded view showing the several elements constituting the adjustable mounting of the armature.

While the invention is susceptible of various modifications and alternative constructions, I have shown in the drawings and will herein describe in detail the preferred embodiment, but it is to be understood that I do not thereby intend to limit the invention to the specific form disclosed, but intend to cover all modifications and alternative constructions falling within the spirit and scope of the invention as expressed in the appended claims.

In devices of the type to which this invention relates, the speaker unit conventionally embodies a suitably supported sound vibration producing means, generally designated 10 in the drawings, and what may be termed a motor or driving means, indicated at 11, by which electrical vibrations are transformed into mechanical vibrations and transmitted to the sound vibration producing means. The desired result is, in the present device, produced by the effect of a permanent magnetic field upon a movable armature which is variably magnetically energized by varying or alternating electrical currents passing through an associated voice coil, the responsive movements of the armature being suitably transmitted to the device for producing sound vibrations.

With particular reference to Figs. 2, 5 and 6, a preferred form of driving means 11 embodies the following structure and arrangement of parts. A flat base 12, preferably of elongated, somewhat oval shape, has outstanding from one side thereof integrally formed supports or posts 13 which may be rectangularly arranged as shown. These posts secure what may be termed a pole piece assembly to the base in definitely fixed relationship thereto. The pole piece assembly comprises a pair of spaced plates 14, 15 which support therebetween a pair of pole pieces 16, 16^a. Each pole piece, as shown in Figs. 2 and 6, preferably consists of a stack of laminations which are substantially U shaped (see Fig. 2). On the outer sides of the legs of each lamination are projecting nibs 17 providing elongated ribs on the complete pole assemblies or pole pieces which are fashioned for engagement with slots 18 provided in the spaced plates 14, 15. The slots are so formed as to receive the ribs snugly whereby precisely and securely to mount the pole pieces between the supporting plates.

As shown in Fig. 2, the relative arrangement of the pole pieces is with the open faces of the U-shaped assemblies opposed to but spaced from each other so that the pole pieces together define a channel which has a central transverse gap and faces along the major dimension of the supporting plates and base. In assembly, one of the supporting plates, in this instance the plate 14, abuts the base 12 and the corners 5 of said plate are cut away to clear the posts 13. The other plate overlies the posts and is apertured to allow screw threaded extensions 19 on the posts to pass therethrough. Nuts 20 threaded onto said extensions rigidly secure the pole 10 piece assembly to the base. If desired other screws 20^a through the base and engaging the base abutting plate 14 may be employed finally to secure the parts permanently together.

While the pole pieces 16, 16^a may be magnetically energized in any suitable manner to 20 produce a permanent magnetic field therebetween the present embodiment attains this end by means of a pair of permanent magnets 21 which are U shaped and are of somewhat greater overall dimensions than the base 12. The magnets are disposed in end to end relation with their like poles abutting and with their meeting faces located substantially on the transverse median line of the pole pieces, as 25 shown in Fig. 6. Thus, the pole pieces 16, 16^a have opposite polarity and the magnetic attraction between each magnet and the pole pieces is ample to hold the magnets in place 30 against endwise movement outwardly. The magnets rest against the base 12 at one side and the open face defined by the other side thereof may be suitably closed and the magnets held in place by a cover member 22 (Fig. 5) which is preferably secured by nuts 23 threaded 35 onto the extensions 19 of posts 13.

The structure thus far described comprises the means by which a permanent magnetic field is produced in the present device. Operatively located within this field is an armature having 40 a voice coil closely associated therewith so that the armature will be magnetically energized in accordance with electrical current variations passing through the voice coil. The attraction and repulsion action resulting from such variable magnetization of the armature in the permanent magnetic field causes the armature to move accordingly. As may be seen clearly in 45 Fig. 5, the armature comprises a stack of laminations 24 of rectangular form which are secured together by pins 25 passing therethrough from 50 end to end. The armature is dimensioned substantially to fill the space between the pole pieces but is of slightly less thickness than the width of the space between the pole pieces to 55 provide a relatively small clearance between each side of the armature and the pole piece opposed thereto.

The armature is surrounded by a voice coil, the structure of which preferably comprises a 60 supporting case 26 of a thin dielectric material formed to provide an outwardly facing channel within which a number of turns of wire 27 are wound. The case 26, as shown in Fig. 6, is centrally open to fit closely yet loosely about the 65 armature and is dimensioned to fit snugly (see Figs. 2 and 8) within the channel defined by the U-shaped pole pieces 16 and 16^a. This snug fit positions the voice coil against other than longitudinal movement of the coil assembly 70 through the channel. To prevent longitudinal 75

movement, lugs 28 outstanding from the voice coil case 26 are provided for engagement with the opposite side faces of at least one of the pole pieces. Thus, the voice coil assembly may be definitely and accurately fixed with respect 5 to the pole pieces.

The armature 24 must be supported in accurately spaced relation between the active faces of the pole pieces. In the present embodiment the means for supporting the armature not only permits the clearance to be adjusted precisely but additionally permits the force which opposes displacement of the armature to be quickly and accurately adjusted. Moreover, the armature supporting means allows the voice coil to be positioned in the closest possible relation to the armature without interfering with armature movements whereby to obtain the magnetic energization of the armature by the energized voice 10 coil with maximum efficiency.

As may best be seen in Fig. 5, a pair of elongated arms 29 have flat end portions 30 which abut the end laminations of the armature stack and are rigidly secured thereto by the pins 25. The arms project in this instance through registering apertures 31 in the base 12 and supporting plate 14. Overlying the outer face of each arm 29 and end portion 30 is a plate 32 which is rigidly secured to the assembly by the pins 25 and by rivets 33 or the like. Each of the plates 32 carries a bridge-like member 34 in the form of a U-shaped structure having diverging arms and dimensioned to fit over or straddle the voice coil structure.

The assembly of one of the plates 32 with its bridge member 34 is best shown in Fig. 4 and is relatively important since it provides a simple but exceedingly accurate means for securing these parts together. Thus, the plate 32 has apertures 35 and 36 through which the rivet 33 and pins 25 respectively extend in securing the plate to the armature assembly. The end of the plate opposite that at which the aperture 35 is located has an intermediate end recess 37 providing spaced longitudinally extending nibs 38. One diverging leg of the bridge member 34, which leg is designated 39, has notches 40 cut in its opposite side faces near the end thereof to receive the nibs 38 when the parts are moved together at right angles to each other. The other diverging leg, designated 41, has a centrally located end projection 42 which is adapted to be received within an aperture 43 appropriately formed on the plate 32. Thus, when the nibs 38 and notches 40 are engaged and the bridge member forced sideways to position the projection 42 in the aperture 43, a binding engagement between the nibs 38 and the margins of the notches 40 results. The projection 42 may then be secured to the plate 32 in any suitable manner, as by soldering, to complete the assembly. In consequence, the bridge member 34 may be secured to the plate 32 in a very simple manner which nevertheless insures that all necessary accuracy will be obtained.

Each bridge member 34 has a flat base portion designated 44 which contains spaced apertures 45 adapted to receive tongues 46 on a flat bar 47. A permanent connection between these parts is obtained in any suitable manner as by soldering. 70 The bars are arranged to extend outwardly from the base 44 at right angles thereto, and to the plate 32, and the parts are arranged so that the longitudinal line of the bars 47 lies substantially on the center line or pivotal axis of the armature. 75

means provided a means of the assembly being of like polarity and thereby engaged and provided support for movement.

The bars 47 are the means by which the armature is supported for movement. The bars 47 are dimensioned to extend between the posts 13 at the ends of the base 12 and substantially to the inner surfaces of the permanent magnets 21 when the parts are assembled. Referring to Figs. 5 and 7, the base 12 near each end thereof has an outstanding lug 48 across which the bars 47 extend. The lugs and the mounting means associated therewith are substantially identical and only one construction will therefore be described.

The outer face of each lug 48 is provided with a semi-circular recess 49 (Figs. 7 and 9) adapted to receive a semi-cylindrical bearing 50. The center on which the arcuate surfaces of the recess and bearing are formed is substantially the pivotal axis of the armature. Opposite the arcuate surface on the bearing is a channel 51 dimensioned snugly to receive the bar 47. Opposed recesses 52 are provided in the sides of the channel to receive lugs 53 formed on a plate 54 which is arranged to overlie the bar 47 after it has been positioned in the channel. A binding plate 55 is secured to the lug 48 by screws 56 and the plate extends across the recess 49 in the lug for engagement with the outer face of the plate 54.

With respect to the operation of mounting the armature structure and adjusting the position of the armature relative to the pole pieces, the bar 47 is positioned in the channel 51 between the bearing 50 and the plate 54, the bearing is placed in the recess 49, and the binding plate, by means of the screws 56, is caused to engage the outer face of the plate 54. It will be evident that by tightening or loosening one or the other of the screws 56, a slight rotational movement of the bearing 50 in the recess 49 may be produced and this movement is utilized to adjust the armature to a desired operative position between the opposed faces of the pole pieces. As may be seen in Figs. 5 and 9, the bearing 50 is somewhat longer than the thickness of the lug 48 to permit adjustment of the position of the bearing and its operating plate 54 along the length of the bar 47. Since movement of the armature produces a torsional strain in the bars 47, the resistance which is offered to movement by the armature may be adjusted to a proper value by locating the bearing 50 at a proper point along the bar 47.

It will be evident from the foregoing that the armature may thus be accurately set in its proper operating position with respect to the pole pieces and that the resistance to movement imposed on the armature may be easily and accurately adjusted.

The arms 29 which extend outwardly from the armature assembly beyond the base 12 converge, as may be seen in Fig. 5, and at their outer ends are joined by plates 57. From these plates a short link 58 extends at right angles for connection with the apex of a cone 59 which herein constitutes the sound vibration producing means 10. This cone is supported by a generally conventional cone mounting in the form of a stamping 60 to which the marginal edge of the cone is suitably connected as at 61. The cone mounting is generally conical, has a cup-shaped apex, and is fashioned to extend about the rear face 70 of the cone. A portion of the mounting near the apex thereof is struck outwardly and offset rearwardly, as at 62, to terminate in a flat portion 63. Other portions, designated 64, are struck out of the cone mounting between the apex and the 75 rim thereof to provide flat surfaces which are

substantially parallel to the struck-out part 63. The base 12 on its outer surface thereof has an upstanding lug 65 intermediate its ends and near one side of the base and has other outstanding lugs 66 spaced longitudinally of the base adjacent to the other side thereof. The arrangement of these parts is such that the struck-out portion 63 is disposed outside of and in abutment with the lug 65, while the struck-out portions 64 are in abutment with the outer sides of the lugs 10 66. The abutting parts are suitably secured together as by screws 67. Thus, a triangular arrangement is provided for supporting the cone mounting from the base or frame of the driving mechanism and the assembly is exceedingly rigid. 15 If desired, an insulated distributor 68 for cooperation with the lead wires from the voice coil may be secured to the lug 65 by the associated screw 67.

It will be seen from the foregoing that a speaker unit has been provided which embodies an improved arrangement of structure and a novel arrangement of parts. Structurally, the various elements which comprise the unit are capable of being produced by simple manufacturing processes. The assembly of the various elements into 25 a complete structure may be easily accomplished and once the parts have been assembled, the only adjustments that are necessary may be quickly and accurately made.

I claim as my invention:

1. In a magnetic speaker, the combination of a pair of permanent magnets disposed in end to end abutting the magnets and crossing the line of engagement between the magnet ends, said pole members being opposed but spaced from each other and the legs thereof defining a channel extending lengthwise of the magnet assembly, an armature in the space between the pole members, a voice coil assembly located in said channel and encircling said armature with the coil in closely and symmetrically spaced relation thereto throughout, said voice coil assembly having a snug fit in said channel and having means thereon interengaging a pole member to prevent movement thereof longitudinally of said channel, supporting means secured to said armature at each end and straddling said voice coil structure, a frame supporting said magnets and pole pieces, adjustable means for connecting said supporting means with said frame, a sound vibration producing device, and means for operatively connecting said armature with said device including arms connected with opposite ends of said armature.

2. In a speaker, the combination of means providing a permanent magnetic field, a stack of laminations constituting an armature located in said field and having a voice coil in closely encircling relationship thereto, and means for operatively supporting said armature including a plate secured to each end of the armature and extending beyond the opposite sides thereof, one extending end having alined notches in opposite sides thereof and the other end being substantially centrally apertured, a U-shaped bracket for each plate having diverging side arms and adapted to pass about the voice coil at that part of the assembly, one side arm having nibs fashioned to fit into said alined notches upon insertion in a direction substantially at right angles thereto and to perfect a binding engagement between the parts when the other end is engaged with said plate, said last mentioned end having

- a part engageable within said aperture for securing the parts together, an outwardly extending arm fixed centrally to each bracket and extending therefrom substantially on the center line of the armature assembly, means connecting with said arms for operatively supporting said armature assembly, and means connected with said brackets and extending substantially at right angles to said arms for connection with a sound vibration producing device.
3. In a speaker, the combination of means for producing a permanent magnetic field, an armature located in said field and having a voice coil in closely encircling relationship thereto, and means for operatively supporting said armature including a plate secured to the armature abutting each end thereof, a U-shaped bracket for each plate having side arms dimensioned to pass about the voice coil at that part of the assembly, one side arm having nibs fashioned to fit into said alined notches upon insertion in a direction substantially at right
- 5
- 10
- 15
- 20

angles thereto and to perfect a binding engagement between the parts when the other end is secured to said plate, and means fixed to each bracket and extending therefrom substantially on the center line of the armature assembly for operatively supporting said armature assembly.

4. In a speaker, the combination of means for producing a fixed magnetic field, a stack of laminations constituting an armature located in said field and having a voice coil in closely encircling relationship thereto, and means for operatively supporting said armature including a plate secured to the armature abutting each end thereof, a U-shaped bracket for each plate having side arms dimensioned to pass about the voice coil, means for securing said brackets to said plates, means connected with said brackets for operatively supporting said armature, and means connected with said brackets and extending substantially at right angles to said armature for connection with a sound vibration producing device.

WILLIAM A. ELLMORE.
